(No Model.)

B. TRYON.

ICE PLOW.

No. 273,192.

Patented Feb. 27, 1883.

UNITED STATES PATENT OFFICE.

BENJAMIN TRYON, OF COXSACKIE, ASSIGNOR TO EMILE HENRY LACOMBE,
OF NEW YORK, N. Y.

ICE-PLOW.

SPECIFICATION forming part of Letters Patent No. 273,192, dated February 27, 1883.

Application filed July 14, 1882. (No model.)

To all whom it may concern:

Be it known that I, BENJAMIN TRYON, of Coxsackie, in the county of Greene and State of New York, have invented a new and Improved Ice-Plow, of which the following is a full, clear, and exact description.

The object of the invention is to lock the cutters at different points of adjustment and take the usual wear from the blades.

Reference is to be had to the accompanying drawings, forming part of this specification, in which similar letters of reference indicate corresponding parts in all the figures.

Figure 1 is a perspective view of a portion 15 of an ice-plow the blades or plows of which are made in accordance with my invention. Fig. 2 is a sectional elevation of one of the blades, taken on the line $x x$, Fig. 1. Fig. 3 is a side elevation of the body of one of the blades, and 20 Fig. 4 is a perspective view of one of the cutters removed from the body or blade.

A A represent the main parts or blades of the plows. B B represent the separate steel cutters, and C C represent the wedges.

25 The bodies or blades A are made curved or circular at their forward edges, and are stepped on the bottom, as shown at a , and are held between the beams D D of the frame of the plow by means of the bolts b b, in the ordinary manner. The forward curved or circular edges of 30 the said blades or bodies are formed with the tongues c, as shown in the drawings, extending the whole length of the blades.

The cutters B B are made curved or circular, and are formed with the groove d to match the curved edges and tongue c of the blades A, as shown clearly in Figs. 1 and 2. The forward edges of the cutters B B are grooved for a portion of their length, as shown at e, 40 and the rear edges of the curved wedges are formed with the tongues f to match the grooves e, as will be understood from Fig. 2, so that when the wedges are driven in the frame of the plow, as shown in Fig. 1, the cutters B B

45 and wedges C C will be locked firmly in place upon the bodies A and held against all danger of lateral movement. At the lower ends the cutters B B are beveled off, as shown at i, so that when in place the lower ends of the cutters will continue in the same slant with the

inclined portions g of the bottom of the blades or bodies—the slant required for producing an effective cutting-point. The forward edges of the cutters and wedges are by preference made sharp and somewhat wider than the 55 thickness of the bodies A, as shown in Fig. 2, so that they will properly clear the gutters cut in the ice or snow and fine particles of ice formed by the plow. By this construction, when the cutters become dull, they may be 60 easily removed by drawing out the wedges and sharpened by grinding or filing, and as easily replaced, and when the cutters become worn they may be set downwardly to take up the wear, thus greatly increasing the durability of 65 the plow.

The beams D D are formed with the offsets h, as shown in Fig. 1, for the wedges C C to come against when driven into place for holding the cutters.

70 Other means for attaching the cutters to the bodies or blades and the wedges to the cutters besides the tongue-and-groove joints—as, for instance, dowel-pins moving in slots; or other means—might be used and not depart 75 from the spirit of my invention.

As ordinarily constructed, the cutting-blades of ice-plows are made in one piece of metal, usually of soft steel, and when the cutting-point thereof wears away the entire surface of the 80 foot or bottom of the cutting-blade must be dressed off by means of a file; or an entirely new blade must be substituted. This work involves the loss of much time, cost, and labor, while by repeated filing the blades become so 85 much reduced as to be useless. By the use of my improvements all of these difficulties are overcome, and the blades of the plow are rendered enduring, as they never become worn, all the wear being sustained by the adjustable 90 cutters.

Having thus described my invention, what I claim as new, and desire to secure by Letters Patent, is—

1. A cutter, B, grooved at e, in combination 95 with a wedge, C, having tongue f, and beams D, having the offsets h, whereby the cutter may be locked at any point of adjustment, as described.

2. The combination, with the body A, hav- 100

ing the tongue *c*, of the removable cutter *B* and wedge *C*, the cutter being formed with the grooves *d* and *e* and the wedge having the tongue *f*, substantially as described.

- 5 3. An ice-plow having the blade *A*, with the under side running in a straight line, *g*, from the shoulder to the point, whereby the wear is thrown upon the ends of the cutters and the blades are rendered much more durable.
- 10 4. The beams *D* *D*, formed with the offsets *h* *h*, in combination with the body *A*, remova-

ble cutter *B*, and wedge *C*, substantially as and for the purposes set forth.

5. The curved body *A* and the curved removable cutter *B*, in combination with the wedge *C* and frame of the plow, made with offsets, substantially as and for the purposes described.

BENJAMIN TRYON.
